UNITED STATES PATENT OFFICE.

RUDOLPH LINDEMANN, OF NEW YORK, N. Y.

STORAGE BIN OR BUNKER.

1,200,206.

Specification of Letters Patent.

Patented Oct. 3, 1916.

Application filed July 1, 1914. Serial No. 848,352.

To all whom it may concern:

Be it known that I, RUDOLPH LINDEMANN, a citizen of the United States, and a resident of the borough of Bronx, city, county, 5 and State of New York, have invented new and useful Improvements in Storage Bins or Bunkers, of which the following is a specification.

This invention relates to storage bins or 10 bunkers of the kind employed for storing coal, grain, etc., and has for its object to provide a bin which may be cheaply and quickly erected from stock construction materials and largely from parts requiring no 15 special fitting.

A further object of the invention is to provide a bin which will sustain a large load but which is of comparatively light construction.

20 A further object of the invention is to provide a bin which will be thoroughly protected from corrosion from destructive elements that may be present in the material stored.

25 With the above objects in view my invention consists in the improved construction hereinafter described and illustrated in the accompanying drawings, in which,

Figure 1 is a side elevation showing a 30 portion of a bin of indefinite length; Fig. 2 is a transverse sectional view upon an enlarged scale; Figs. 3, 4, and 5 are detail views which will be later described; and Fig. 6 is a detail of a modification.

35 Referring now to the drawings 1 indicates the supporting columns which may be of structural iron or steel, from the top of which the bin proper is suspended. Attached to the top of the columns are plates 2 in which 40 are supported the continuous, inclined plate girders 3 extending longitudinally between the columns 1. The frame structure is braced with suitable cross beams 4 and 5 above and below the bin, and with such 45 longitudinal and diagonal braces 6 as may be necessary to support the load for which the bunker is designed. The bunker proper is suspended from the plate girders 3 and

is formed of reinforced concrete of a special construction to be described, and shaped 50 to provide inclined sides, forming practically extensions of the girders 3, and connected by a curved bottom.

In the preferred construction as illustrated in Fig. 2 the plate of the girder 3 55 extends beyond its base angle 3^a and clamped to this extension at suitable intervals along the girder are clevises 7 in which are screw-threaded the ends of the suspension rods 8 which support the walls of the 60 bin. The rods 8 are bent like the ribs of a boat and extend from the girder on one side to that on the other, the construction of course being identical on each side. Supported on the rods 8 and attached thereto 65 by clips 9 is a continuous sheet of metal fabric 10, such as employed in reinforced concrete construction.

In my improved construction any approved reinforcing fabric may be employed 70 but I prefer to use a fabric of the character indicated diagrammatically in Fig. 3 which consists of alternate widths of expanded metal having between these widths ribs 10^a formed by crimping an uncut width 75 of the metal. The clip 9 which I have shown is especially designed for attaching this form of fabric to the rods and comprises a flat split ring for encircling the rod and an upstanding tongue 11 adapted to 80 project between the walls of the rib to which it may be fastened by a suitable pin or by merely punching through the rib and the tongue, so that the bur of the rib will engage the hole in the tongue. 85

The clips 9 may be formed by stamping out the sheet metal and are very quickly applied without special tools for the purpose. The function of the clips is merely to hold the fabric in place until the cement is applied, and as they support none of the load, they may be light enough to bend around the rod by hand. After the fabric is fastened in place the interior of the bin is lined with a thick coat of cement-mortar or concrete 90 12 95 and is plastered outside between the rods 8

so that the fabric is entirely embedded in the cement.

As indicated the bin may be built in any desired length by simply duplicating the sections shown in the drawings. The ends of the bin are formed of vertical walls of the construction shown particularly in Figs. 2 and 4. Suspended from the end cross beam 4 at spaced intervals are lengths of channel iron 13 whose lower ends are connected to the side walls of the bin by means of anchor rods 14 projecting through the channels and embedded in the cement 12. Attached to the inner face of the channels is a sheet of metal fabric whose lower edge terminates just above the level of the fabric of the side walls which is bent up at the end as shown in Fig. 4 to form an overlapping joint with the end sheet. The end sheet of fabric may be fastened to the channels in any approved manner, for instance, by suitable clips 17 somewhat similar to the clips 9 but having a single flat tongue adapted to bend under the flat web of the channel instead of around the rod 8. A flat stay 18 may be attached to the fabric at the other side of the channel to hold the fabric against lateral movement. The end wall is plastered on both its inner and outer surfaces in the same manner as the side walls, so that the entire surface of the bunker which contacts with the material to be stored is of cement. At intervals the bunker is provided with outlet gates 15 which may be of any suitable construction, here shown as metal chutes having flanges at their upper edges embedded in the cement of the bottom of the bin.

In Fig. 6 I have shown an alternate method of connecting the rods 8 with the plate girder 3. As shown in this figure the clevises 7 are dispensed with and the threaded ends of the rods project through the flange of the lower angle of the girder and are supported by nuts engaging the upper face of the flange. The stiffeners 16 with which the girder is provided at intervals support the flange of the girder against distortion.

In my improved construction the material for the bin may be readily shipped in knock-down form occupying very little space. The expanded metal fabric may be had in bales of comparatively small size relative to the area of the fabric when spread out. The rods 8 need not be bent to accurate shape but are preferably shipped simply bent in a loop and with their ends attached together. The attaching clips 9 may be set at any point along the rods or fabric, so that no special fitting of the parts is required except in the ordinary structural iron work of the supporting frame. When the rods are applied

their ends are easily drawn apart and all the rods will have substantially the same 65 curve.

Having thus described my invention, what I claim and desire to secure by Letters Patent is:

1. In a suspension bin, the combination of 70 a supporting frame work having its upper longitudinal edges formed of girders, a series of parallel suspension rods connected at each end to the opposite girders with their ends extending downwardly and inclined 75 toward each other and having the intermediate connecting portion curved, an open mesh fabric having stiffening ribs at intervals supported on said rods with the ribs extending longitudinally of the bin, connecting members rigidly attached to said ribs and encircling said rods, the portion of the connecting members encircling the rods being adapted for coöperation with the rods 80 at any point in their lengths. 85

2. In a suspension bin, the combination of 90 a supporting frame work having its upper longitudinal corners formed of inclined girders, a series of parallel suspension rods connected at each end to the opposite girders and extending substantially in the direction of the inclination of said girders with the intermediate connecting portion curved, an open mesh fabric having stiffening ribs at intervals supported on said rods, clips 95 connecting said fabric and said rods comprising a part attached to said ribs and a bifurcated part adapted to loosely encircle said rod at any point in its length, and a covering layer of mortar or concrete laid on 100 said fabric.

3. A suspension bin comprising a supporting structure, a series of parallel suspension rods connected at each end to the opposite longitudinal sides of said supporting structure and extending downwardly with their middle portion curved to form a bottom for said bin, an open mesh fabric having stiffening ribs at intervals supported on said rods with the ribs extending longitudinally of the bin, clips connecting said fabric and said rods comprising tongues attached to the ribs at intervals and forks having their arms bent loosely around said rods, and a coating of mortar or concrete laid on 110 said fabric. 115

4. A suspension bin comprising a supporting structure, a series of parallel suspension rods connected at each end to the opposite longitudinal sides of said supporting structure and extending downwardly with their middle portion curved to form a curved bottom for said bin, an open mesh fabric having stiffening ribs at intervals supported on said rods with the ribs extending longitudinally of the bin, clips con- 120 125

necting said fabric and said ribs comprising tongues attached to the rods at intervals and forks having their arms bent loosely around said rods, a coating of mortar or concrete laid on said fabric, and end walls for said bin comprising a series of channel irons suspended from said supporting structure, a metal fabric laid against said channel irons, clips connecting said fabric and 10 said irons, a lining of concrete or mortar

laid on said fabric, and anchor bolts set in the ends of said channel irons and embedded in the lining of said side and bottom walls.

Signed at New York, in the county of New York and State of New York, this 20th 15 day of June, 1914.

RUDOLPH LINDEMANN.
